FLOATING TANK ROOF DRAIN

John H. Wiggins, Chicago, Ill.

Application August 20, 1945, Serial No. 611,590

3 Claims. (Cl. 220—26)

1

This invention relates to floating tank roof drains of the type that comprise a hose or other suitable conduit that will accommodate the rise and fall of the floating roof, connected at its upper end to the roof and having its lower end extending through or connected to a stationary part of the lower end portion of the tank.

One object of my invention is to provide a floating tank roof drain of the general kind above mentioned, which is of such design or construction that it can be removed and replaced without liability of subjecting the workmen performing the operation, to danger resulting from gases in the gas space of the tank, such, for example, as inhaling poisonous gases, or causing gases to be ignited by a spark from the metal tools or parts used to attach the drain to the part or parts with which it co-acts.

Another object is to provide an efficient means of simple design and inexpensive construction for preventing an air pocket from being created in the hose or flexible conduit of a floating tank roof drain of the general kind mentioned.

And still another object of my invention is to provide a floating tank roof drain which is of such design or construction that, in the event the hose or other flexible conduit of same breaks in two, both parts of said hose or conduit can quickly and safely be removed from the interior of the tank. Other objects and desirable features of my invention will be hereinafter pointed out.

Figure 1 of the drawings is a vertical transverse sectional view of a floating tank roof equipped with a drain constructed in accordance with my invention.

Figure 2 is a detail view, illustrating in side elevation, one of the devices on the underside of the floating roof that is used to control the shape and prevent excessive bending of the hose or flexible conduit of the drain.

Figure 3 is a sectional view of the means used to detachably connect the lower end portion of the hose to the tank side wall; and

Figure 4 is a sectional view of the means used to detachably connect the upper end portion of the hose to the floating roof.

In the accompanying drawings, which illustrate one form of my invention, A designates the side wall of a tank that is adapted to hold liquid, B designates the bottom of said tank, and C designates a conventional floating roof that floats on and is supported by the liquid D in the tank. Said floating roof is provided with a drain that leads from the top side of the roof, and which is of such design or construction, that it will accom-

2

modate the vertical movement of the roof when the roof rises and falls, due to changes in the level of the liquid D. In the preferred form of my invention herein illustrated, said drain comprises a flexible hose 1 that is capable of floating in the liquid D, and the upper and lower ends of said hose are detachably connected to the roof C and to the tank side wall A, respectively.

My invention comprises

10 (1) An improved means for detachably connecting the lower end portion of the hose 1 to the tank side wall A;

(2) An improved means for detachably connecting the upper end portion of said hose to the floating roof C;

(3) A novel means for removing the hose from the interior of the tank in the event said hose breaks into two separate pieces; and

(4) A novel means for controlling the shape of the hose so as to prevent an air pocket from being created in the hose.

The means used to connect the lower end portion of the hose to the tank side wall, consists of a nipple 2 that is preferably cemented to the lower end portion of the hose 1, a flange plate 3 on said nipple rigidly connected to same by welding or in any other suitable manner, a pad plate 6 on the exterior of the tank side wall A, arranged over an opening in said wall, that is of greater diameter than the flange plate 3, bolts or threaded studs 5 rigidly attached by liquid-tight joints to the flange plate 3 and projecting outwardly from same through an annular series of holes in the pad plate 6, a gasket 4 between the plates 3 and 6, and nuts 7 on the bolts 5 arranged on the outer side of the pad plate 6. It will be noted from Figure 3 that the flange plate 3 is arranged on the inside of the pad plate 6, and that said flange plate 3 is larger than the hole in the pad plate through which the nipple 2 projects outwardly.

The means used to detachably connect the upper end of the hose to the floating roof C, consists of a nipple 12, preferably cemented to the hose 1 and welded or rigidly connected in any other suitable way to a removable closure plate 10 that normally closes a hole in the roof C, and stud bolts 9 for detachably connecting the closure plate 10 to an annular supporting plate 8 attached to the roof, so as to form a rim for the hole in the roof which the plate 10 normally closes, said supporting plate 8 being provided in its top side with blind, tapped holes for the studs 9, and a gasket 11 being arranged between the closure plate 10 and the supporting plate 8, on

which it bears, so as to produce a gas-tight joint between said parts.

In order to facilitate the removal from the tank of the two parts of a hose that has broken in two, a relatively thin corrosion-proof cable 14 is attached at one end to the nipple 2 at the lower end of the hose 1, and attached at its other end to the nipple 12 at the upper end of the hose. Said cable 14 is the same length, or slightly longer than the hose, and is preferably attached to the hose in any suitable way at intervals of from five to ten feet. Subsequently, I will describe how said cable is used to remove a broken hose.

Unless the hose 1 is maintained in a certain approximate shape or position during the rise and fall of the roof C, a sharp, angular bend might form in the hose. This would be objectionable, because sharp bends cause rapid wear and deterioration, and they also produce air pockets which interfere with drainage. My improved drain comprises abutment members 13 and 13^a on the underside of the roof C, constructed and arranged so that when the roof moves upwardly towards the position represented by the broken line C', in Figure 1, the hose will assume the shape or position represented by the broken line 1' in said figure, and will effectively be prevented from bending at a sharp angle. Preferably, the members 13 and 13^a are formed from metal rods attached to the underside of the roof and bent into the form of loops, whose horizontal cross pieces or hose contacting portions are wide enough so that they will compensate for lateral flexing of the hose and always engage or contact the hose 1, no matter which way said hose bends laterally as the roof rises and falls. They add little to the cost of the structure, but they eliminate the possibility of the hose bending into such a shape as to produce an air pocket.

The hose 1 is first installed from the inside of the tank by pushing the nipple 2 on the lower end of the hose outwardly through the pad plate 6 on the tank side wall, and simultaneously positioning the rigid bolts 5 on the flange plate 3 in the openings provided for said bolts in the pad plate 6, the gasket 4 having previously been positioned on the nipple 2 in engagement with the outer face of the flange plate 3. Thereafter, the nuts 7 of the bolts 5 are tightened by a workman located on the outside of the tank side wall. After the upper end of the hose has been cemented to the nipple 12 on the closure plate 10, said closure plate with the gasket 11 positioned on the underside of same, is fastened to the supporting plate 8 on the roof by means of the stud bolts 9 which are inserted and tightened by a workman located on the top side of the roof.

If the hose breaks in two, a new hose can be installed and the two parts of the old hose can be withdrawn from the tank, without the necessity of a workman entering the gas space of the tank, or reaching into the gas space and manipulating a wrench or other metal tool that might produce a spark in the gas space which would result in an explosion. To replace a broken hose, the level of the liquid in the tank is lowered to a point below the hole in the pad plate 6 on the tank wall, as shown in broken lines in Figure 1, wherein the reference character D designates the lowered liquid level. The flange plate 3 on the nipple 2 at the lower end of the hose is then released from the pad plate 6 by removing the nuts 7 on the bolts 5 which project outwardly through the pad plate 6, after which the workman, who is standing on the exterior of the side wall of the tank, attaches a trailer cable (not shown) to the

nipple 2 at the lower end of the hose, said trailer cable being located on the exterior of the tank wall. A different workman, who is standing on the top side of the roof C, now unscrews the stud bolts 9 and removes the closure plate 10 to which the upper end of the hose 1 is attached, and then withdraws from the tank the upper part of the broken hose that is attached to the nipple 12 on the closure plate 10, and also the lower part of the hose which is joined to the upper part of the hose by the cable 14, which, as previously stated, extends lengthwise of the hose and is attached to same at intervals along the length of the hose. This operation causes the trailer cable to be drawn into the tank through the hole in the pad plate 6 at the lower end of the tank, and then upwardly through the interior of the tank to the closure plate opening in the roof C, through which the two parts of the hose were withdrawn by the workman standing on the roof. Thereafter, the workman on the roof detaches the upper end of the trailer cable from the nipple 2 of the broken hose, and then attaches this end of the trailer cable to the nipple 2 of the new hose that is to be installed. At this time, the trailer cable extends from the closure plate opening in the roof to the hole in the pad plate 6 on the tank side wall, and the lower end of said trailer cable is located on the exterior of the tank side wall. The workman standing on the roof then inserts the nipple 2 and flange plate 3 of the new hose through the hole in the supporting plate 8 on the roof, and the workman standing on the ground adjacent the pad plate 6 on the tank side wall, then pulls downwardly on the trailer cable, so as to pull the nipple 2 at the lower end of the hose outwardly through the nipple hole in the pad plate 6. If necessary, a rod or other device can be inserted into the end of the nipple 2 and turned or manipulated so as to line up the bolts 5 on the flange plate 3 with the holes provided for said bolts in the pad plate 6, after which said bolts can be drawn outwardly through the pad plate 6 sufficiently to enable the nuts 7 to be applied to same and then tightened so as to produce a liquid-tight joint between the flange plate 3 on the hose and the pad plate 6 on the tank wall. The final step in the operation is to position the closure plate 10 on the supporting plate 8 on the roof and insert and tighten the stud bolts 9, so as to produce a gas and liquid-tight joint between the floating roof and the closure plate 10, to which the upper end of the hose is attached.

A floating tank roof drain of the construction above described, overcomes the necessity of equipping the floating roof with a manhole for enabling a workman to enter or reach into the gas space of the tank during the operation of replacing a worn or broken hose, and hence, it protects workmen from danger, resulting from inhaling poisonous fumes, or resulting from an explosion caused by a spark from a metal tool that is manipulated inside of the gas space to release or tighten devices used to attach the drain hose to parts with which it co-acts. In my improved drain all of the operations employed in installing and removing the hose 1 are performed entirely on the exterior of the tank, without even reaching into the gas space of the tank, and the holes in the tank roof and tank side wall through which the hose is inserted and removed, are so small that the quantity of poisonous gases capable of escaping through same are not liable to be dangerous to workmen standing in the open.

Also, the construction above described simplifies the operation and reduces the time required to remove from the tank the two parts of a broken hose and to install a new hose and connect it by gas and liquid-tight joints to the floating roof and to the side wall of the tank. Also, as previously explained, my invention eliminates sharp, angular bends in the hose that produce rapid deterioration, or which create air pockets that interfere with drainage. The above described means for detachably connecting the hose to the structure, and the procedure for installing and replacing the hose, can be modified without departing from the spirit of my invention, which, briefly stated, consists in arranging a flexible conduit on the interior of a tank provided with a floating roof, providing said conduit at its upper and lower ends with plates that form closures for openings in the roof and tank side wall, respectively, one of said plates being arranged on the interior of the structure and the other plate being arranged on the exterior of the structure, and providing means, operable from the exterior of the structure for detachably connecting said plates to parts of the structure which they overlap.

Having thus described my invention, what I claim as new and desire to secure by Letters Patent is:

1. The combination of a liquid storage tank, a roof for said tank that floats on the liquid in the tank, a flexible drain conduit for said roof arranged on the interior of the tank and capable of floating in the liquid that sustains the roof, means on the roof for connecting the upper end of said drain to the roof, means on the lower end portion of the tank side wall for connecting the drain to said side wall, the conduit being free to flex intermediate the points where it is connected to the roof and to the tank side wall, and an abutment means for said conduit rigidly connected to

the roof in stationary relationship with same and positioned between said conduit and the underside of the roof, said abutment means having no direct connection with the conduit and being provided with a contacting portion for said conduit located in a horizontal plane lower than the point of attachment of the upper end of the conduit with the roof, whereby said conduit will be prevented from assuming the form of an upwardly-disposed loop in which air can collect and interfere with the flow of the drainage from the top side of the roof through said conduit.

2. A structure of the kind described in claim 1, in which said abutment means is formed by a plurality of depending members on the underside of the roof arranged in spaced relation between the peripheral edge of the roof and the point of attachment of the upper end of the conduit with the roof and provided with horizontally-disposed conduit contacting portions of sufficient width to compensate for lateral flexing of the conduit during the rise and fall of the roof.

3. A structure of the kind described in claim 1, in which said conduit is provided with a cable or the like disposed longitudinally of same and attached at intervals along the length of the conduit.
